ERNEST TEBEAU, OF STOCKTON, CALIFORNIA.

KNIFE-POLISHING MACHINE.

1,147,828.

Specification of Letters Patent. Patented July 27, 1915.

Application filed March 2, 1914. Serial No. 821,868.

To all whom it may concern:

Be it known that I, ERNEST TEBEAU, a citizen of the United States, residing at Stockton, county of San Joaquin, and State 5 of California, have invented certain new and useful Improvements in Knife-Polishing Machines, of which the following is a specification.

This invention is a knife polishing machine, and the primary object of the invention is to provide a device of the class described which is extremely simple in construction, economical to manufacture, yet highly efficient in its operation.

15 The invention embodies a machine wherein a pair of coöperating polishing members are provided; one fixedly mounted for simple rotation, and the other mounted for rotation, but adapted for movement toward or 20 away from the former.

A salient feature of the invention resides in means operable by the article being polished, for impelling the movable polishing member toward, or away from the stationary member.

In one of its practical forms the invention embodies a frame in which is mounted a polishing disk, adapted for rotation but retained against movement relative to said 30 frame; a second polishing disk mounted in said frame for rotation, but adapted for movement toward or away from the first mentioned disk; a lever pivoted to the frame, coöperating with the movable disk, 35 and having the power arm of said lever so positioned as to be engaged by the knife during the process of polishing the same, whereby the operation of polishing the knife automatically causes the coöperating disks 40 to engage the blade of the knife under the required pressure; and means for simultaneously rotating said disks. Means for securing the frame to a rigid support is also preferably provided.

45 Features of the invention, other than those specified, will be apparent from the following description, read in conjunction with the accompanying drawings.

In the accompanying drawing I have 50 illustrated one practical embodiment of the invention, but the construction shown therein is to be understood as illustrative, only, and not as defining the limits of the invention.

Figure 1 is a side elevation of a knife polishing machine embodying the present invention. Fig. 2 is a vertical, transverse section thereof, taken on line 2—2 of Fig. 1. Fig. 3 is a plan view illustrating a bifurcated bell-crank lever which I preferably 60 employ.

Referring to the drawings, A designates a frame formed with a pair of upstanding spaced arms *a*, *a'*, and preferably provided with a depending portion *a*², projected inwardly as at *a*³, and threaded to receive a thumb screw B for the purpose of providing means, whereby the frame may be secured to a rigid support, such as a table or the like. The arms *a* and *a'* are provided 70 near their free ends with oppositely placed, alined bearings *c* and *d*, in which are adapted to be journaled, the spindles C and D, respectively.

The spindle C is in the form of a stub 75 shaft, mounted for rotation in the bearing *c*, but fixed against longitudinal movement by means of the collar *c'*, exterior of the frame, and a pinion E interiorly thereof, both of said members being rigidly secured to said 80 shaft.

The spindle D, which coöperates with the bearing *d*, is provided interiorly of the frame with a broad-faced pinion F, but is of such length as to protrude for some distance beyond the exterior of said frame. The spindle D is thus adapted for movement longitudinally of its axis, but is provided at its outer extremity with a shoulder *d'*. Intermediate the shoulder *d'* and the 90 exterior of the frame A, and arranged coaxially with the shaft D, is a spring G adapted to normally retain said shaft in its exteriorly extended position.

On the adjacent ends of each of the spindles C and D, are fixed face plates H, to which are secured, in any suitable manner, resilient members, *h*, each provided with a suitable facing *h'*. These facings are shown as leather disks, the centers of which are cut 100 out as at *h*². The disks *h'* are adhesively secured to the resilient members *h*, and embody the faces which operate the knife blade during the polishing operation.

Mounted against longitudinal movement 105 in the frame A, below the spindles C and D, is a shaft I. This shaft, which is journaled in the bearings *i* and *i'*, in the arms *a* and *a'*,

respectively, is provided with suitable means for imparting rotation thereto, preferably a crank L, and on said shaft is fixed a pair of gears J and K which mesh with the pinions 5 E and F on the spindles C and D, respectively. Thus, when the crank L is turned, the power generated is transmitted through the shaft I and gears J and K to the pinions E and F, for the purpose of rotating 10 the spindles C and D, whereby the polishing disks h' are rotated in the same direction.

As hereinbefore stated, the spindle D is adapted for longitudinal movement, hence 15 the broad faced pinion F which assures operative connection between the shafts I and D at all times irrespective of the position of the shaft D.

In order that the shaft D may be shifted 20 so that the polishing surfaces of the disks h' will engage with the faces of the knife blade in carrying out the operation of polishing the same, I provide means whereby the placing of the knife in proper position automatically adjusts the spindle D to its correct operative position. This means is embodied in a bell-crank lever O which is pivoted at M to a projecting finger N of the frame A. The lever O is so placed that its 25 work arm o extends upwardly past the outer end of the spindle D, while its power arm o' is bifurcated, and is thus adapted to straddle the working elements of the machine so as to extend across the opening between the 30 polishing disks. A thumb-screw P is threaded through the work arm o, and engages the end of the spindle D, whereby 35 proper adjustment may be had.

The operation of the parts thus far described will be apparent, it being manifest 40 that when the knife is positioned between the polishing disks h' in such manner that the back of the knife blade engages with the upper edge of the power arms o' of the lever 45 O, a downward pressure upon said knife blade will tilt the bell crank on its point of pivoting M. This causes the work arm o to engage the end of the shaft D with a result 50 that said shaft is shifted against the tension of the spring G, to bring the movable polishing member into engagement with the face 55 of the knife blade. For the purpose of allowing the knife blade to be readily positioned between the polishing disks, the free 60 ends of the arms a and a' of the frame, are preferably extended inwardly over the polishing members, and shaped to form a wedge 65 shaped entrance for the knife blade, whereby incorrect positioning of the knife is rendered 70 impossible. If the crank L is now turned, the rotary motion will be imparted through the shafts I, gears J, K, and pinions E and F to the polishing disks h' with the result 75 that the knife positioned between said disks 80 is polished. It will be clear that the greater

downward pressure exerted by the operator upon the knife blade, the greater will be the pressure of the disks h' against the faces of said blade, so that the operator is able at all times to obtain the exact amount of pressure 70 desired.

During the operation of polishing a knife blade, it is often necessary to employ some abrasive, such as *e.g.*, pumice or emery, and I 75 preferably provide means whereby the abrasive shed from the rolls during the polishing operation is receivable in a container, for the purpose of preventing the distribution of such waste upon the table or other support to which the machine is attached. The receptacle referred to is shown in the form of a drawer Q, which is mounted to slide in the ways q, formed in the frame A so that said drawer is easily detachable for removing the accumulated waste from the polishing disks. 80

Having thus fully described the invention, what I claim as new, and desire to secure by Letters Patent is:—

1. In a knife polishing machine, the combination of a frame, a polishing member 90 mounted for rotation thereon, a second polishing member rotatably mounted on the frame and adapted for movement toward and away from the first mentioned polishing member, means for rotating said polishing members in synchronism, and means whereby the placement of the article to be polished in proper position imparts movement to the movable polishing member to bring said member into operative relation to its complementary polishing member, said means operating to move the movable polishing member independently of the means for rotating the polishing members. 95

2. In a knife polishing machine, the combination of a pair of rotatable polishing members one of which is movable toward or away from the other, means for rotating said members, means for normally retaining the movable member in retracted position, 105 and means operable by the placement of a knife between the polishing members for automatically impelling the movable member toward its complementary polishing member, said impelling means being entirely independent of the means for rotating the polishing members, in the carrying out of its function. 110

3. In a knife polishing machine, the combination of a frame, a pair of aligned shafts 120 mounted thereon one of said shafts being stationary and the other movable longitudinally toward and away from the stationary shaft, means for simultaneously rotating said shafts, polishing members mounted on 125 the adjacent ends of the shafts and adapted to operate on a knife blade passed therebetween, means for normally retaining the movable shaft in retracted position, and means operating directly upon the movable 130

shaft and extending across the opening between the polishing members, whereby the positioning of a knife between the polishing members operates said last mentioned means 5 for the purpose of impelling the movable shaft toward the stationary shaft.

4. In a knife polishing machine, the combination of a frame, a pair of alined shafts mounted thereon one of said shafts being 10 stationary and the other movable longitudinally toward and away from the stationary shaft, means for simultaneously rotating said shafts, polishing members mounted on the adjacent ends of the shafts and adapted 15 to operate on a knife blade passed therebetween, means for normally retaining the movable shaft in retracted position, and a lever pivoted to the frame in such manner as to extend across the opening intermediate 20 the two polishing members, said lever being adapted to coöperate with the movable shaft, whereby a knife blade positioned between the polishing member engages with the lever with the result that the movable polishing 25 member is impelled toward its coöperating stationary member, said movement of the movable polishing member being accomplished by the lever independently of the means for rotating the polishing members.

30 5. In a knife polishing machine, the combination of a frame, a pair of coöperating polishing members mounted thereon, one of which is stationary, and the other movable toward and away from the stationary member, means for rotating said members, and a bell-crank pivoted to the frame in such manner that the power arm of said bell-crank extends across the opening intermediate the polishing members and its work 35 arm engages with the movable shaft, whereby the positioning of a knife between the polishing members operates the bell-crank to impel the movable polishing member toward the stationary member.

40 6. In a knife polishing machine, the combination of a supporting frame, a pair of shafts mounted thereon, one of which is stationary and the other movable toward and away from the stationary shaft, means for 45 retaining the movable shaft in retracted position, coöperating polishing members mounted on the adjacent ends of said shafts, means for imparting rotation to said shafts, and a bell-crank lever, the work arm of 50 which is adapted to engage the end of the movable shaft and the power arm of which is bifurcated, whereby it is adapted to straddle the operating parts of the machine so as to extend across the opening between the 55 polishing members with the result that the positioning of a knife between the polishing members operates the bell-crank to impel the polishing member on the movable shaft toward its coöperating member on the stationary shaft.

7. In a knife polishing machine, the combination of a supporting frame, a pair of alined spindles mounted on said frame, one stationary and the other movable toward and away from the stationary spindle, polishing disks mounted on the adjacent ends of said spindles, a spring coöperating with the movable spindle for normally retaining said spindle in retracted position, pinions mounted on both the stationary and movable spindles, a driving shaft, means for rotating said shaft, gears fixed on the driving shaft and meshing with the pinions on the spindles for the purpose of rotating said spindles in synchronism, spindle shifting 70 means mounted on the supporting frame and coöperating with the movable spindle, said spindle shifting means being operable upon the insertion of a knife blade between the polishing disks to impel the movable disk toward the stationary disk, independently of the polishing disk operating means.

8. In a knife polishing machine, the combination of a supporting frame, a pair of alined spindles mounted on said frame, one 90 stationary and the other movable toward and away from the stationary spindle, polishing disks mounted on the adjacent ends of said spindles, a spring coöperating with the movable spindle for normally retaining 95 said spindle in retracted position, pinions mounted on both the stationary and movable spindles, a driving shaft, means for rotating said shaft, gears fixed on the driving shaft and meshing with the pinions on the 100 spindles for the purpose of rotating said spindles in synchronism, the pinion on the movable spindle having a wide face, whereby said wide faced pinion is constantly in mesh with its coöperating gear, irrespective 105 of the position of the movable spindle, and means, independently of the disk operating means in the carrying out of its function, for imparting longitudinal movement to said movable spindle.

9. In a knife polishing machine, the combination of a frame, a polishing member mounted for rotation thereon, a second polishing member rotatably mounted on the frame, and adapted for movement toward 115 and away from the first mentioned polishing member, means for rotating said polishing members in synchronism, and a lever associated with the movable polishing member, and adapted to be directly engaged by 120 the article to be polished, whereby the placement of said article in proper position imparts movement to the movable polishing member, said lever operating to move the movable polishing member independently of 125 the means for rotating the polishing members.

10. In a knife polishing machine, the combination of a pair of rotatable polishing members, one of which is movable toward or 130

away from the other, means for rotating said members, means for normally retaining the movable member in retracted position, and a lever associated with the movable polishing member, and operable directly by a knife placed between the polishing members for automatically impelling the movable member toward its complementary member, said lever being entirely independent of the

means for rotating the polishing members, 10 in the carrying out of its function.

In testimony whereof I have signed my name to this specification in the presence of two subscribing witnesses.

ERNEST TEBEAU.
